US0D1101883S

(12) United States Design Patent (10) Patent No.: US D1,101,883 S
(45) Date of Patent: * Nov. 11, 2025

(54) PADDLE

(71) Applicant: CRBN Pickleball LLC, Costa Mesa, CA (US)

(72) Inventors: Garrett Gosselin, Costa Mesa, CA (US); Nam Hoai Tran, Costa Mesa, CA (US)

(73) Assignee: CRBN Pickleball LLC, Costa Mesa, CA (US)

() Term: 15 Years

(21) Appl. No.: 29/938,827

(22) Filed: Apr. 23, 2024

(51) LOC (15) Cl. 21-02

(52) U.S. Cl. USPC D21/729

(58) Field of Classification Search

(57) CLAIM

The ornamental design for a paddle, as shown and described.

DESCRIPTION

FIG. 1 is a first front perspective view of a paddle, in accordance with the present disclosure;

FIG. 2 is a second front perspective view of the embodiment shown in FIG. 1;

FIG. 3 is a back perspective view of the embodiment shown in FIG. 1;

FIG. 4 is a front view of the embodiment shown in FIG. 1; FIG. 5 is a back view of the embodiment shown in FIG. 1; FIG. 6 is a first side view of the embodiment shown in FIG. 1;

FIG. 7 is a second side view of the embodiment shown in FIG. 1;

FIG. 8 is a top view of the embodiment shown in FIG. 1; and,

FIG. 9 is a bottom view of the embodiment shown in FIG. 1.

The broken lines shown in the figures show features of the paddle that form no part of the claimed design.

1 Claim, 7 Drawing Sheets
